UNITED STATES PATENT OFFICE.

RAYMOND B. SHOEMAKER AND CHARLES L. LAWRENCE, OF NEW YORK, N. Y.

DISHWASHER.

Application filed February 10, 1926. Serial No. 87,222.

Our invention relates particularly to dish washers.

The main object of our invention is to provide a convenient liquid mixer adapted to be connected to water pipes or to other sources of liquids under pressure. Another object is to provide convenient means for the washing of any articles which may be cleaned by the application of liquids, for example, the 10 washing of dishes with a mixture of water and liquid soap. Another object is to provide convenient means for tempering water and mixing soap with it when desired.

The preferred form of our invention comprises a rigid container having a flexible receptacle within it. Provision is made for the entrance of a liquid under pressure within the container to compress the inner receptacle. Both the container and the receptacle 20 are adapted to discharge into a common chamber which is formed so as to accelerate the mixing of the liquids.

Fig. 1 is a front view of one form of a liquid mixer embodying our invention.

Fig. 2 is a plan view of the liquid mixer shown in Fig. 1.

Fig. 3 is an end view of the same liquid mixer.

Fig. 4 is a partly sectional view of the preferred form of liquid mixer embodying our invention. This form may be quickly attached to or removed from the conventional hot and cold water faucets.

Fig. 5 is a side view of the form of liquid mixer shown in Fig. 4.

Fig. 6 is a plan view of a detail.

Fig. 7 is a sectional view of the same.

The container 10 may be made of any rigid material suitable for holding water or other liquids under pressure. It is connected to sources of liquid supply such as faucets 11 and 12, by pipe sections 13 and 14 and has an outlet member 15 and a flexible discharge pipe or hose 16 to provide means for discharging the liquids under pressure and for directing a jet or spray against the surfaces to be cleaned or sprayed in any suitable manner. The container has a cover 17 adapted to be secured to the container in an air tight manner by screws 18.

The cover has an inlet opening for soap closed by a cap 19. Fig. 4 shows a slightly different arrangement of faucets 11' and 12'.

Within the container 10 is a flexible bag or

receptacle 20, for instance, of soft rubber 55 adaptable for holding fluids. This receptacle rests on a perforated platform 21 having supporting lugs 22 so that water pressure can be applied. The rim of the receptacle is compressed between the container 10 and the cover 17. This arrangement forms an air-tight seal between the container and its cover and at the same time holds the flexible receptacle in the position shown in Fig. 4. The receptacle 20 has a discharge member 65 23 having a control valve member 24. The discharge member 23 is smaller than the discharge outlet 15 and is designed to occupy a position within it substantially as shown in Fig. 4. The outlet 23 may be secured to the 70 bottom of the receptacle 20 by a nut 25.

The member 23 and its valve 24 constitute in effect parts of the outlet member. A pipe section 26 connected to the reservoir 10 is connected to a socket member 27 in an extensible manner. A soft rubber bushing member 28 is adapted to fit over the end of the faucet 11' in a water tight manner. The connection to the faucet 12' is effected in the same manner, so that the apparatus can be 80 readily attached to any ordinary pair of hot and cold water faucets.

In operation, the flexible receptacle 20 is first filled with a suitable liquid such as soap. Then the faucets are opened to provide hot or cold water in the proportion desired. The water (or other liquid) coming into the container flows out of the discharge member 15 and at the same time exerts a pressure against the sides of the flexible receptacle 20 and 90 forces out the soap in a quantity which may be regulated by the valve member 24.

The liquids readily mix in the tapered section of the discharge member 15 and flow out of the hose 16 to be discharged against the 95 articles to be cleaned or sprayed.

Any suitable form of discharge nozzle with or without a brush such as 30 may be employed.

The discharge pipe 16 in Figs. 1, 2 and 3 is 100 shown as swivelled so that it can be turned into the various positions shown. In the form shown in Fig. 4 the flexible hose 16' is detachable and the brush 30 is also detachable.

This liquid mixer has proven itself to be 105 very convenient and serviceable in the washing of dishes and other household utensils.

It is also adaptable to a variety of uses such as supplying tempered water, washing automobiles, spraying fruit trees and disinfection.

- 5 It can also be used for shampooing, sterilizing, etc. In each case, of course, the chemical or substance to be mixed with the water or other liquid will be placed in solution form in the collapsible container 20 and forced out 10 when water is flowing and the valve 24 is open.

We claim:

1. Apparatus of the character described comprising a container having an opening in its upper part for the insertion of a bag, an inlet valve for admitting water to said container, an outlet member having a passage for water and having a neck projecting upwardly with a soap discharge passage leading to 20 the water passage, a collapsible bag mounted in the container and having an inlet mouth at its upper part and an outlet in the bottom, means for detachably securing the outlet in the bottom of the bag on the neck of the outlet member, means for detachably securing the mouth of the bag in the opening in the container and closing the opening and the mouth, and a valve for controlling the soap discharge passage.
- 30 2. Apparatus of the character described comprising a container having an opening at the top with a detachable cover, hot and cold water inlet pipes connected to the opposite sides of the container, an outlet member connected to the bottom of the container, a collapsible bag mounted in the container and having a mouth at its upper end secured in place by said cover and removable independently of either of said pipe connections, the bottom of said bag being detachably connected to said outlet member, said outlet member having a passage discharging from said bag and a valve for controlling said passage.
- 45 3. Apparatus of the character described comprising a container having a valve-controlled water inlet at one side and an opening for inserting a bag, an outlet member secured to the bottom of the container and having a water passage and a soap passage, a collapsible bag conforming to the shape of and substantially filling the inside of the container and having an inlet mouth and an outlet, means for detachably securing said inlet mouth to the opening in the container and closing the opening, means for securing the outlet of said bag to the outlet member and a valve in the outlet member for controlling the discharge from the bag through the soap passage, the pressure of water in the container when the inlet valve is open serving to compress the bag and slowly eject its contents when the valve in the outlet member is also open.
- 65 4. Apparatus of the character described comprising a container having a valve-con-

trolled water inlet at one side and an opening in the top for inserting a bag, an outlet member secured to the bottom of the container and having a water passage and a soap passage, a collapsible bag conforming to the shape of and substantially filling the inside of the container and having an inlet mouth in the top and an outlet in the bottom, means for detachably securing said inlet mouth and closing the opening in the top of the container, a detachable clamping member inserted through the mouth of the bag for securing the outlet of said bag to the outlet member and a valve in the outlet member for controlling the discharge from the bag through the soap passage.

5. Apparatus of the character described comprising a container having an opening for the insertion of a bag, an inlet valve for admitting water to said container, an outlet member having a passage for water and having a neck projecting upwardly with a soap discharge passage leading to the water passage, a collapsible bag mounted in the container and having an inlet mouth, means for detachably securing the bottom of the bag on the neck of the outlet member, means for detachably securing the mouth of the bag in the opening in the container and closing the opening and the mouth, and a perforated plate surrounding said neck and holding said bag spaced apart from the bottom of the container so as to permit water to flow beneath the bag to the water passage.

6. Apparatus of the character described comprising a container having an opening at the top with a detachable cover, hot and cold water inlet pipes connected to the opposite sides of the container, a water outlet pipe connected to the bottom of the container, a collapsible bag mounted in the container and having a mouth at its upper end closed and secured in place by said cover, said bag being removable through said opening independently of either of said pipe connections, an outlet nozzle from the bottom of said bag and a clamp insertable through the mouth of the bag for detachably connecting the bottom of the bag to said outlet nozzle.

7. Apparatus of the character described comprising a container having a valve-controlled water inlet at one side and an opening in the top for inserting a bag, outlet means at the bottom of the container having a water passage and a soap passage, a collapsible bag substantially conforming to the shape of the inside of the container and having an inlet mouth at the top and an outlet at the bottom, means for detachably securing said inlet mouth to the opening in the container and closing the opening, means insertable through the mouth of the bag for securing the outlet of said bag over the soap outlet passage and a valve for controlling the discharge from the bag through the soap passage.

8. A dish washer comprising a container, a hot water inlet and valve at one side thereof and a cold water inlet and valve at the other side, an outlet member at the bottom 5 of said container having a water outlet passage and a valved soap passage, a perforated platform surrounding the upper end of said

outlet member and a collapsible receptacle for liquid soap supported on said platform, said valved passage being in communication 10 with said receptacle.
